HOIST

Moulton M. Lucas, North Dartmouth, Mass.

Application September 21, 1943, Serial No. 503,249

1 Claim. (Cl. 212—8)

The present invention relates to new and useful improvements in hoists, and has for its primary object to provide, in a manner as herein-after set forth, a device of this character comprising a novel construction and arrangement, whereby engines and transmissions may be expeditiously lifted out of motor vehicles and moved from place to place with a minimum of effort.

Other objects of the invention are to provide a hoist of the aforementioned character which will be comparatively simple in construction, strong, durable, highly efficient and reliable in use, compact, and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a top plan view of a hoist constructed in accordance with the present invention.

Figure 2 is a view in side elevation thereof.

Figure 3 is a fragmentary view in cross-section, taken substantially on the line 3—3 of Figure 2.

Referring now to the drawings in detail, it will be seen that the embodiment of the invention which has been illustrated comprises a base structure which is designated generally by reference character 1. In the embodiment shown, the base 1 includes a pair of spaced, parallel beams 2 of channel iron which are mounted on casters 3. A platform 4 in the form of a metallic plate is secured on one end portion of the beams 2.

Mounted on the beams 2 at an intermediate point and rising therefrom is a pair of channel iron posts or uprights 5. Channel iron braces 6 extend between the posts 5 and the rear end portions of the beams 2. The structure is further stiffened by an inclined metallic brace 7 extending between the posts 5.

As illustrated to advantage in Figure 3 of the drawings, aligned brackets or arms 8 in the form of I beams are mounted on the upper portions of the posts 5 and extend inwardly therefrom. The inner ends of the brackets 8 are spaced from each other. Braces 9 are provided for the brackets 8. Mounted on the adjacent end portions of the brackets 8 is a shaft 10. A vertically swinging boom 11 in the form of an I beam is

mounted at an intermediate point on the shaft 10. Eye bolts 12 are mounted beneath the end portions of the boom 11. A hoisting chain 13 is connected to the eye bolt 12 at the front end of boom 11.

Journalized in suitable bearings 14 which are provided therefor on the posts 5 is a shaft 15. Journalized between the rear end portions of the beams 2 is a roller 16. A cable or the like 17 is trained under the roller 16 and has one end connected to the eye bolt 12. The other end of the cable 17 is secured to the shaft 15 for winding thereon. A hand crank 18 on one of the posts 5 is operatively connected to the shaft 15 by gears 19. A dog 20 is engageable with one of the gears 19 for releasably securing the shaft 15 against retrograde rotation.

It is thought that the operation of the device will be readily apparent from a consideration of the foregoing. Briefly, the hoist is moved on the casters 3 to a point adjacent the vehicle with the boom 11 projecting thereover or thereinto. The forward end of the boom 11 is then swung downwardly and the chain 13 is secured to the engine or transmission to be removed. The shaft 15 is then actuated through the medium of the hand crank 18 for winding the cable 17 on said shaft, thus swinging the forward end of the boom 11 upwardly for elevating the engine or transmission. When the engine or transmission has been lifted sufficiently to clear the vehicle, the hoist, with said engine or transmission suspended from the boom 11, is moved to any desired location on the casters 3. Of course, the apparatus may also be used for replacing the engine or transmission.

It is believed that the many advantages of a hoist constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A hoist of the character described comprising a base including a pair of spaced, parallel beams, casters mounted beneath said beams, a platform mounted on one end portion of the beams, a roller journalized between the other end portions of said beams, a pair of posts rising from the beams at intermediate points in said beams, braces extending between the posts and said other end portions of the beams, a brace ex-

tending between the posts, a boom mounted, at an intermediate point, for vertical swinging movement between the posts, means on one end portion of the boom for connecting said boom to a load to be lifted, a shaft rotatably mounted on the upper portions of the posts below the boom, a cable trained under the roller and having one end extended upwardly and rearwardly from the roller and connected to the other end

portion of the boom, the other end of said cable being extended upwardly and forwardly from the roller and secured to the shaft for winding thereon, and a hand crank on one of the posts operatively connected to the shaft for actuating same for winding the cable thereon for swinging the boom in a direction to elevate the load.

MOULTON M. LUCAS.
